UNITED STATES PATENT OFFICE.

ALFRED J. VELANDER, OF KNOXVILLE, ILLINOIS.

SAW.

No. 868,509.

Specification of Letters Patent.

Patented Oct. 15, 1907.

Application filed July 18, 1906. Serial No. 326,787.

To all whom it may concern:

Be it known that I, ALFRED J. VELANDER, a citizen of the United States, residing at Knoxville, in the county of Knox and State of Illinois, have invented 5 new and useful Improvements in Saws, of which the following is a specification.

This invention relates to saws, being especially directed to an improved power attachment for driving the saw in one direction, and has for its objects to produce a comparatively simple, inexpensive device of 10 this character which may be conveniently attached to the saw and arranged for operating the same, one whereby the saw will be automatically driven in its cutting direction, and one whereby the outer spring 15 may be quickly adjusted at will for regulating the driving force imparted to the saw.

With these and other objects in view, the invention comprises the novel features of construction and combination of parts more fully hereinafter described.

20 In the accompanying drawings: Figure 1 is a side elevation of a saw equipped with an attachment embodying the invention and showing the same in position for use. Fig. 2 is a similar view as seen from the other side of the casing. Fig. 3 is a horizontal sectional view taken centrally and longitudinally through the spring receiving casing, on the line 3—3 of Fig. 1. Fig. 4 is a cross section taken on the line 4—4 of Fig. 2. Fig. 5 is an elevation showing a slightly different embodiment of the invention. Fig. 6 is a section taken 25 centrally and longitudinally through the casing. Fig. 7 is a cross section taken on line 7—7 of Fig. 6.

Referring to the drawings, 1 designates a saw provided along one edge, as usual, with teeth 2 and having at one end a handle 3 adapted to be grasped for 30 operating the saw, the other end of which is connected by a cable or other flexible element 4 with a power spring 5 arranged within a tubular casing 6 having a cap 7 rotatively fitted onto its rear end and provided at its forward end with a pair of downwardly extending 35 ground engaging members or arms 8 having their normally lower ends sharpened as at 9, there being formed adjacent the rear end of casing 6, a lateral rearwardly opening tubular portion or throat 10 through which the cable 4 plays, as more fully hereinafter explained.

Formed on the cap 7 and extending into the casing 6 is a conical tensioning head 11 which enters the adjacent end of the spring 5 and is provided at its forward end with a cross-piece or arm 12 arranged to travel in 40 the coils of the spring during rotation of the cap, while journalized at the forward end of the casing is a grooved guide pulley 13 on which the cable 4 is arranged to travel during operation of the saw, the pulley being preferably located at a point adjacent the forward end 45 of the tubular portion 10, whereby the cable may play freely through the mouth of said portion and will dur-

ing rearward movement of the saw exert traction in a direct axial line on the spring 5 in expanding the same.

The casing 6, which is provided in its side wall opposite the pulley 13 with a door 14 designed for normally closing and opening, through which access may be had to the pulley for lubricating or other purposes, has attached to its front side at a point adjacent its rear end a guide strip 15 designed to guide the saw in its movements, there being also attached to the top wall 65 of the casing a bell 16 adapted for the reception of a strap or the like through the medium of which the device may be conveniently transported, while the cable 4 has its inner end attached to a conical block or head 17 entered into the adjacent end of the spring and provided with a transverse engaging piece or pin 18 engaged between the coils of the spring.

Pivoted to the rear side of the casing at a point adjacent its rear end by means of a pivoting member 19 is a pair of coöperating log-engaging members or clamps 75 20, 21, of which the former has at its forward end a rearwardly curved sharpened spur 22 and is provided on the upper edge of its shank portion with teeth 23 adapted for engagement by a pawl 24 pivoted to the clamping member 21, which latter is formed at its upper end 80 with a hand piece 25 and at its lower end with a forwardly curved, sharpened engaging portion or spur 26. The clamping member 20 has its shank provided with a plurality of relatively spaced openings 27 through any one of which the pivoting member 19 may be entered 85 in attaching the clamps, thus to permit relative adjustment of the members to effect a proper initial position of the sharpened engaging portions 22, 26, toward or from each other.

In practice, the device is set up for use by planting 90 the lower sharpened ends of the arms 8 into the ground and embedding the engaging portions or spurs 22, 26 of the clamping members into the log for holding the casing and saw in proper position on the latter. In operating the saw, the handle 3 is grasped and the tool 95 drawn rearwardly, thereby exerting traction on the cable 4 for expanding spring 5, and after the blade has reached the limit of its rearward movement it is pressed downward on the log and moved forward, this action being effected through the medium of the spring 5 in 100 contracting, it being understood, of course, that the cutting of the log is accomplished during forward movement of the saw.

It will be observed that by turning the cap 7 the cross piece 12 will act in the coils for lengthening and 105 shortening the spring according to the direction of rotation of the cap, thus to increase or decrease the tension of the spring and consequently its force or power.

In the form of device illustrated in Figs. 5, 6 and 7, the saw is arranged for operation in connection with a 110 saw horse or buck 28, to the upper end of one bar of which the upper end of casing 6 is attached, as at 29,

the lower end of the casing being arranged to rest upon the ground, the construction being in other respects practically identical with that above described, except that in this form the spring 5' extends throughout 5 the entire length of the casing, the cable 4 being extended centrally through the spring and attached to a block 17 which is in turn engaged with the coils of the spring at a point near its rear end, whereby in the 10 operation of the saw the spring will upon rearward movement of the latter be compressed as distinguished from the expansive action of the spring as shown in the form at first described.

Having thus described my invention, what I claim is:

- 15 1. In a device of the class described, the combination of a casing forming a support, a saw slidably mounted thereon, a spring housed in the casing, a guide pulley at one end of the casing, a flexible element passing around the pulley and extending into the casing and having its ends connected with a saw and the spring, clamps secured to the 20 casing for gripping a log, and legs at the opposite end of the casing, and a handle for operating the saw connected with the end thereof adjacent the clamping means.
2. In a device of the class described, the combination of

a hollow casing forming the body of the device and having 25 a lateral opening adjacent one end, a helical spring mounted in the casing and secured at one end, a flexible element extending longitudinally into the casing and attached to the free end of the spring, means at the said opening around which the flexible element moves back and forth, a 30 saw disposed parallel with the body and shorter than the latter, the outer end of the said element being connected with the saw, and a handle on the saw at the end thereof opposite from that connected with the element, the saw being free to move longitudinally and laterally in a plane 35 parallel to the axis of the casing.

3. In a device of the class described, the combination of a hollow member, lugs at one end thereof, gripping jaws at the opposite end, a helical spring, an adjustable means for varying the number of active coils of the spring, a pulley 40 mounted on the member, a saw disposed along one side of the member and guided thereon, and a flexible element passing over the pulley and connected at its end with a saw and spring.

In testimony whereof, I affix my signature in presence 45 of two witnesses.

ALFRED J. VIELANDER.
